US00D969845S

(12) **United States Design Patent** (10) Patent No.: **US D969,845 S**
(45) Date of Patent: **** Nov. 15, 2022**

(54) **DISPLAY SCREEN OR PORTION THEREOF
WITH A GRAPHICAL USER INTERFACE**

(71) Applicant: **Lemon Inc.**, Grand Cayman (KY)

(72) Inventor: **Jiacheng Yang**, Culver City, CA (US)

(73) Assignee: **LEMON INC.**, Grand Cayman (KY)

(**) Term: **15 Years**

(21) Appl. No.: **29/798,518**

(22) Filed: **Jul. 8, 2021**

(51) LOC (13) Cl. **14-04**

(52) U.S. Cl.

USPC **D14/486**

(57) **CLAIM**

The ornamental design for a display screen or portion thereof with a graphical user interface, as shown and described.

DESCRIPTION

The FIGURE is a front view of a display screen or portion thereof with a graphical user interface showing the new design.

The outermost broken line rectangle illustrates a display screen or portion thereof and forms no part of the claimed design. The remaining long dash-long dash and short dash-short dash broken lines illustrate portions of the graphical user interface that form no part of the claimed design.

1 Claim, 1 Drawing Sheet
